HOSIERY

Lester D. Wagenhorst, Reading, Pa., assignor to
 The Nolde and Horst Company, Reading, Pa.,
 a corporation of Pennsylvania

Application October 2, 1941, Serial No. 413,243

4 Claims. (Cl. 66—96)

My invention relates to weft-knitted hosiery having a turned welt top portion, and to its production on a straight-bar or full-fashioned knitting machine;

My primary object is to provide for turning a very short welt, if desired, as little as one-half inch, not heretofore deemed possible, and giving a novel and pleasing effect of a ribbon-like finish to the top of the stocking.

Another object is to provide a novel initial loop course to be engaged by the welt bar in a manner to facilitate transfer back to the needles in turning a welt, requiring less exactness in re-engagement, and forming an improved and less bulky line of junction with the course of loops with which it is interknitted.

Another object is to provide a novel tension take-up means which may engage in the short welt and initially lie close to the needles and free of contact with the loop forming sinkers, dividers and knock-over bits.

Another object is to provide for these improved results without disturbance or interference with the usual known knitting machine mechanism.

With the aforesaid objects in mind, and with other objects that will later herein appear, my invention comprises the new method and means for producing the same, hereinafter more fully described in connection with the accompanying drawings, the novel features of which are particularly set forth in the appended claims.

Fig. 1 is a conventional side view of a stocking embodying a preferred very short top welt portion in accordance with my invention.

Fig. 2 is a much enlarged diagrammatic plan view showing of an initial weft laid yarn projected between the needles to form a usual course of loops.

Fig. 3 is a like plan view, showing the loops of Fig. 2 engaged by the hooks of a welt bar, with alternate loops held from engaging in the beards of their needles.

Fig. 4 is another like plan view showing several courses of the knitted fabric, and the welt bar hooks engaging and holding spread the initial course of loops.

Fig. 5 is another like plan view showing the spread loops being transferred onto the needles, the knitted fabric underlying the turned portion of the welt being omitted as confusing to a clear disclosure, but indicating a portion of my novel take-up bar in place within the turned welt portion.

Figs. 6 and 7 are enlarged diagrammatic cross-sectional elevations of a needle bar such as in-

10 dicated in Figs. 2 to 5, with its associated sinkers, dividers, and knock-over bits; Fig. 6 indicating a welt bar hook engaging a loop of my special initial course, and a picot bar point holding a loop away from engaging under a needle beard; and Fig. 7 showing the turned welt with the initial course of loops reengaged on the needles, and my novel take-up bar engaged with 15 in the turned welt and lying free of contact between the sinkers and knock-over bits.

Fig. 8 is a separate small scale plan view of my novel take-up bar; and Fig. 9 a cross sectional view of the same indicating bridge on which it travels and means for preventing its turning on 20 its longitudinal axis during such travel.

The making of full-fashioned weft-knitted stockings is of course well known, as well as the means employed to form a turned welt, comprising a welt-bar to engage the initial course of loops and transfer them to the needles in a subsequently knitted fabric course, at which time a 25 rod is ordinarily inserted within the turned welt and attached to a take-up roll so as to exert a necessary draw-off tension on the fabric being knitted. The turned welt thus formed is a recognized commonly employed way of securing the otherwise free end loops of the initial course, and the depth of this welt has varied with custom and demand, but is necessarily of a depth of approximately two inches as the narrowest welt that could be practically made commercially. This approximate length was the practical minimum to insure manual pressing off of the loops from the welt-bar to the needles, and to space 30 the take-up rod out of the path of the advancing sinkers and dividers and away from the knock-over bits.

The desirability of simplifying the loop transfer from the welt bar and making it free from 35 faults due to a missed loop engagement, as well as the making of a narrower welt to save time and material in knitting the stocking, has long been recognized, but not practically possible heretofore. The manner and means for making my improved welt now to be fully described, 40 accomplishes both the aforesaid objects in a feasible and commercially productive manner, with a less bulky and more elastic course of the interknitted loops of the initial and terminal 45 courses of the web fabric and with a pleasing narrow welt giving a ribbon-like finish to the top of the stocking.

Referring to the drawings, Fig. 1, indicating a 50 stocking embodying my invention, the leg portion 1 and foot portion 2, are knitted as here-

tofore, and this figure shows my new narrow turned-welt 3, which may be as little as one-half inch in depth, as contrasted with the usual welt of approximately four inches in depth, and the heretofore minimum of approximately two inches. The portion 4 below the narrow turned welt 3, may be knitted as desired, but is preferably made of a somewhat heavier yarn with several picot courses as indicated both for guarding against runs and for a pleasing appearance, this portion 4 ordinarily extending about the depth of the usual deep turned-welt and terminating well above the knee of a wearer.

My improved initial course of knitting to facilitate loop transfer from a welt bar to the needles, as illustrated in the drawings, is made as follows: A yarn carrier is traversed along the line of needles 6 to lay an initial weft 5 to the rear of the needles, which weft is formed, as heretofore, by the advancing sinkers and dividers 7, into sinker loops projecting forwardly between the needles, each of which loops is then engaged on its respective hook 8 of a welt bar having a hook for each sinker loop thus formed. At this point I provide for a special dipping operation of a usual picot bar, having picot points 9, 9 arranged to cooperatively engage the loop bends on alternate needles as heretofore. The picot bar movement is then arrested and, instead of shifting laterally to transfer its engaged yarn bends onto the adjacent needles, as in making a picot course, is for this special purpose moved upwardly, so that upon descent of the needles 6, the yarn bends engaged by points 9, will ride over, instead of under, the beards of their needles 6, and clear the latter; the pull of the welt bar hooks drawing these needle loops to the front of their needles, as shown. An initial course of sinker loops 10 is thus formed, as indicated in Fig. 4, having substantially one half as many loops as originally formed, and each loop is held laterally spread by its engagement with two hooks 8 of the welt-bar.

With the initial course of loops 10 thus formed and held by the welt-bar hooks 8, the picot-bar is withdrawn, and knitting, as usual, started to produce the necessary length of fabric to form the turned welt. For the present desirable narrow welt shown, approximately only one inch of fabric is required, at which point knitting is arrested, and the welt turned.

It is not possible to employ the usual take-up rod in this short welt, as it would interfere with the advancing sinkers and dividers which would tear and cut the fabric, and I therefore employ a special take-up bar 15, as later herein more fully described.

The loops 10 are transferred to the needles 6 by alining the welt bar hooks 8, with said needles; and due to the loops 10 being held in laterally spaced relation extending over two fabric wales, as shown, they readily and freely engage over two needles without the need of meticulous accuracy, or pressing down as heretofore; and while desirable that each loop 10 engage on two needles 6, it is not essential, and should one needle be missed, the other needle engagement would lock the loop against starting a run. When the welt is thus easily and quickly turned, knitting is resumed to finish the stocking as heretofore. My improvements do not interfere with the location of usual picot stitch courses as to finish the top of the turned welt, or located as desired for other purposes, as in the fabric below the turned welt, 75

which as before stated may be made of heavier yarn if desired.

The new and improved turned welt and the construction thereof is set forth and claimed in my original application, now issued as Patent No. 2,260,960, dated October 28, 1941.

In order to provide a proper draw-off tension of the fabric being knitted, the requirement for which is well known and understood in the art, 10 I employ a special take-up bar 15, before referred to, and shown particularly in Figs. 8 and 9. This bar, as shown, is preferably comparatively thin and flat, of a width preferably less than one-half inch, and a length sufficient to span across a needle section of a machine so its ends may rest on usual side bridges 17 and travel thereon under pull of spaced straps 16, 16, from a usual take-up roll, not shown. The ends of this bar are preferably of reduced width and notches 18, 18 are provided to hold the straps 16, 16 from shifting their positions. These reduced width ends, as shown, desirably, but not necessarily, engage under guard track 19 on the side bridges so the bar will not turn on its longitudinal axis.

This bar 15, as before described, is laid within the turned welt, and as the strain of take-up tension thereon is in the plane of its flat width, giving a strength against bowing under pull of the straps 16, 16, practically equivalent of a round 30 rod having a diameter equal to its width. And its ends being engaged under the guard tracks 19 are prevented from turning axially to maintain this resistance to bowing.

The bar 15 being thin and narrow, may readily 35 be set within even the short turned-welt above described, and when thus engaged, it may lie between the sinkers and dividers, and the knock-over bits, as seen in Fig. 7, without danger of contact with the former as they are advanced during their usual operation. This bar 15 may 40 of course be used for deeper turned-welts, and functions in the manner of usual take-up rods, with the added advantage of use for very narrow turned-welts as described.

My invention, above fully described, fully accomplishes my stated objects: The special loops 10 of the initial course greatly facilitate transfer to the needles from the welt bar, and, as they eliminate the heretofore necessary hand pressing 50 down of the loops, permit of a very narrow turned welt, close to the needles, and leaving small space for such hand pressing. Should the loops miss the desired engagement with both needles to which they are intended to be transferred, engagement with one needle will prevent any danger 55 of runs caused by such miss. And with my thin flat take-off bars a narrow turned-welt may be given proper tension without contact or interference with the advanced sinkers and dividers.

The particular construction above specifically described, may of course be modified and changed within the spirit of my invention as defined in the following claims.

What I claim is:

1. In a full fashioned stocking knitting machine, the method of knitting a turned welt, which comprises forming an initial course of alternating needle and sinker loops, engaging each sinker loop on the hook of a welt bar, disengaging the loops from alternate needles by dipping action of a picot bar, to form intermediate sinker loops each held laterally spread by engagement with two welt bar hooks, knitting a plurality of usual fabric courses to a predetermined welt junction course, transferring each spread sinker

loop to two needles in said junction course, interknitting each spread loop with said two needle loops in said junction course, and then completing the knitting of the stocking.

2. In a full fashioned stocking knitting machine, the method of knitting a turned welt, which comprises forming an initial course of alternating needle and sinker loops, engaging each sinker loop on the hook of a welt bar, disengaging every other loop from its needle by dipping 10 action of a picot bar to form one-half the original number of sinker loops each spread laterally by engagement with two welt bar hooks, knitting a plurality of usual fabric courses to a predetermined welt junction course, laying a thin 15 flat take up bar on said fabric in front of the needles, between the sinkers and knock over bits, turning the fabric over said bar and transferring each spread loop from said welt bar hooks to two needles in said welt junction course, interknit- 20 ting each of said spread loops with two needle

loops in said junction course, and then completing the knitting of the stocking.

3. A tension take-up bar for forming the turned welt of a weft-knitted stocking made on a full-fashioned knitting machine, which comprises a thin flat bar adapted to lie within the turned welt close to the row of needles and in a plane between and free from contact with the sinkers and knock-over bits of said machine.

4. A tension take-up bar for forming the turned welt of a weft-knitted stocking made on a full-fashioned knitting machine, which comprises a thin flat bar adapted to lie within the turned welt close to the row of needles and in a plane between and free from contact with the sinkers and knock-over bits of said machine; said bar having laterally projected flat ends arranged to slidably engage lateral bridge tracks to prevent turning of said bar on its longitudinal axis.
